Bruce Ford
BY
Augustine B. Stoughton,
ATTORNEY.

UNITED STATES PATENT OFFICE.

BRUCE FORD, OF PHILADELPHIA, PENNSYLVANIA.

PLATE TERMINAL FOR STORAGE BATTERIES.

Application filed June 9, 1920. Serial No. 387,543.

To all whom it may concern:

Be it known that I, BRUCE FORD, a citizen of the United States, residing at Philadelphia, in the county of Philadelphia and State of Pennsylvania, have invented a certain new and useful Plate Terminal for Storage Batteries, of which the following is a specification.

The principal objects of the present invention are to shorten the average path for current, to provide the same conductivity while reducing the quantity of metal employed, and to permit of the arrangement of the plate lugs in nearly the axis of the post.

15 The invention comprises the relative arrangement, combination and construction of parts to be presently described and finally claimed whereby the above and other objects hereinafter set forth are accomplished.

20 Reference will be made to the accompanying drawings forming part hereof and in which—

25 Figure 1, is a top or plan view of a plate terminal for storage batteries embodying features of the invention.

Fig. 2, is an elevation of the same, and

Fig. 3, is a side view of Fig. 2.

In the drawings 1, is a vertically arranged member tapering to provide uniform cross-section from the horizontal plate 2, to the vertical post 3. The plate 2, is horizontal and to it the plate lugs 4, are connected. The plate 2, is shown as toothed and from this it must be understood that in the course of manufacture the plate lugs 4, are inserted between and attached to these teeth in such a way that a unitary character is imparted to the structure. The vertical post 3, attached to the top of the vertical member 1, is of circular cross-section and terminates in a cylindrical or conical portion to which the cell

connections are made and below which the jar cover and seal connections (not shown but well understood) are applied. The post and plate being of the same effective cross-section, that cross-section is maintained uniform by the member 1, which is appropriately tapered for the purpose. The lateral portions of the part 1, taper upwardly, Fig. 2, to the post 3, and the centrally arranged post extension 5, tapers downwardly from the post, Fig. 3, so that the part 1, has a double taper.

The vertical arrangement of the member 1, in the described combination with the vertical post 3, and horizontal plate 2, is advantageous in that it gives a shorter average path for the current, less metal for the same conductivity, and permits of the plate lugs being, if desirable, carried more nearly to the axis of the vertical post.

I claim:

1. A plate terminal for storage batteries consisting of a unitary structure comprising in combination, a plate for attachment to the plate-lugs, a tapering member arranged at right angles to the plate with its wider end nearest the plate, and a post of circular cross-section mounted on top of the narrower end of the member and aligned with the member, substantially as described.

2. A plate terminal for storage batteries consisting of a unitary structure comprising in combination a plate for attachment to the plate-lugs, a post of circular cross-section, and a member disposed at right angles with the plate and connecting the post and plate and laterally tapering from the plate towards the post and centrally tapering from the post towards the plate, substantially as described.

BRUCE FORD.
